UNITED STATES PATENT OFFICE.

CARL L. BAUSCH, OF ROCHESTER, NEW YORK, ASSIGNOR TO BAUSCH & LOMB OPTICAL COMPANY, OF ROCHESTER, NEW YORK, A CORPORATION OF NEW YORK.

LENS-GRINDING MACHINE.

Application filed September 1, 1921. Serial No. 497,560.

To all whom it may concern:

Be it known that I, CARL L. BAUSCH, of Rochester, in the county of Monroe and State of New York, have invented certain new and useful Improvements in Lens-Grinding Machines; and I do hereby declare the following to be a full, clear, and exact description of the same, reference being had to the accompanying drawings, 10 forming a part of this specification, and to the reference numerals marked thereon.

This invention has to do with grinding apparatus and relates more particularly to machines for grinding optical lens blanks 15 to the desired thickness, the chief object being to provide a simple and practical machine for conveniently and rapidly grinding a portion of one side of a lens to an accurately measured predetermined distance from the opposite side of the lens to form a mark serving as a guide in the subsequent final grinding of the lens to the desired thickness. To these and other ends the invention consists in certain improvements and combinations of parts, all as will be hereinafter more fully described, the novel features being pointed out in the claims at the end of the specification.

In the drawings:

30 Figure 1 is a front elevation of a machine embodying the present invention.

Figure 2 is a similar view showing the parts in a different position.

Figure 3 is a top plan view.

35 Figure 4 is an elevation as seen from the right in Figure 1.

Figure 5 is an enlarged sectional elevation on the line 5^a—5^a of Figure 3.

40 Figure 6 is a fragmentary detailed view of the lens holding device and cutting element in operation.

Figure 7 is a detailed view of a micrometer part employed in the machine.

45 Figure 8 is a sectional view on the line 8^a—8^a of Figure 5.

Figure 9 is a detail elevation of the lens holding device as shown in Figures 1 and 2, with a cover plate removed to expose the actuating means.

50 Figure 10 is a detail view of one of the parts of the lens holding device.

Similar reference numerals throughout the several views indicate the same parts.

In the manufacture of optical lenses it has been a common practice, during the 55 grinding of the lens to the desired thickness, to take measurements from time to time in order to ascertain when the lens blank has been brought to the thickness desired. This has been a more or less troublesome factor in the operation for several reasons. It has required interruption of the 60 operation to make successive measurements of the blank. Furthermore, for the purpose of the grinding operation, the blank is usually fixed on a holder by an adhesive in a manner well known in the art so that its 65 edge or periphery only is accessible for measurement. As the thickness at the lens center is commonly different from that at its edge portion, and as the center thickness is the dimension generally prescribed, it has been necessary to calculate the corresponding 70 thickness for the lens edge portion in order to make the measurements. Not only has this consumed time and decreased the rate of production but the method, being of a more or less cut and try character, has resulted in inaccuracies and lack of uniformity in the result. The present invention on the other hand provides apparatus 75 for conveniently and rapidly forming a central mark or cut in one side of the lens extending to a distance from the opposite side equal to the desired thickness of the blank so that the latter is thus provided 80 with a thickness indicating guide mark and may then be placed in the grinding apparatus and the surface ground away until the guide mark is reached and the blank brought to the desired thickness. The machine of course comprises adjustable measuring or gage means to insure the accurate 85 location of the guide mark, as more fully appears from the following detailed description.

95 Referring more particularly to the drawings, the machine comprises a frame indicated generally at 15, Figures 1 and 2, having a base or bed portion 16 from which rise spaced bearings 17 and 18 for a shaft 19 rotatably carried therein. The shaft is extended toward the right from bearing 18 over the bed portion of the frame and has fixed in any suitable manner adjacent its end the grinding or cutting element 20. 100 105

The cutting element 20 is in the present instance in the form of a comparatively thin disk of any suitable abrasive material for cutting a groove or kerf in the side of 5 a lens to a depth sufficient to form at its bottom a guide mark indicating the amount to which the surface of the lens is to be ground away in a subsequent operation to reduce the lens to the desired thickness, it 10 being understood that the predetermined thickness is measured between the bottom of the cut thus made and the opposite side of the lenses.

Shaft 19 supporting and rotating the cutting element may be driven by any suitable means, and in the present instance is provided between its bearings 17 and 18 with tight and loose pulleys 21 and 22 for a belt drive. A guard 23 is preferably provided 15 for the cutting element and is supported on the adjacent bearing 18. A pipe 24, Figures 2 and 5, carried by and extending upwardly from the guard serves as a means for supplying the cutting element with a lubricant which may be conducted to the pipe by means connected with its open upper end.

A lens holding device, in which a lens blank may be conveniently gripped, carries the lens during the operation and comprises 20 gage means in the form of an anvil for contact with the side of the lens opposite the cutting element. The gage means, or anvil, on which the lens rests, and the cutting element, are moved toward and from each 25 other with the lens located therebetween and the degree of approach of these parts is controlled to mark the lens for subsequent grinding to the predetermined thickness. It is obvious that either or both the gage 30 means and cutting element may be moved for this purpose, the motion in the present instance being imparted to the gage means or anvil.

As a support for the lens holding device 35 the frame bed 16 has fixed thereon a vertical standard or post 25, Figure 5, of cylindrical shape on which slides vertically a sleeve 26 actuated by means presently to be described. The lower end of the sleeve 40 carries an arm 27 extending over the bed of the machine, the outer end of the arm carrying the gage means or anvil comprising preferably a stud or post 28 the upper end of which is finished with a convex gage 45 surface for engagement with the under side of the lens indicated at 29. On either side of the anvil 28 sleeve 26 carries spaced parallel arms 30 and 31 which are relatively movable on the sleeve toward and from 50 each other and provided with fingers or studs 32 for gripping the edges of the lens at points spaced about its periphery.

The means for movably supporting arms 55 30 and 31 on the sleeve comprises preferably vertically spaced parallel guideways

or tracks 33, Figure 5, formed in a substantially channel shaped member 34 fixed on the sleeve. The inner end of arm 30 slides on the lower track 33 and has a vertical extension 35, Figures 9 and 10, at the 70 upper end of which is a transverse slide or shoe 36 sliding in the upper track 33. The other lens gripping arm 31 carries at its inner end a transverse slide or shoe 37, Figures 5 and 9, sliding in the lower track 75 33, and arm 31 is provided at the same end with a vertical extension 38, the upper end of which slidably engages the upper surface of the upper track 33. As shown in Figures 5, 9 and 10, the vertical extensions 80 35 and 38 of arms 30 and 31 respectively, are each in the form of a relatively thin plate disposed forwardly of and clearing the shoe of the other arm. Arms 30 and 31 therefore are supported on tracks 33 for sliding movement toward and from each other for gripping with their fingers 32 the peripheries of lenses of various shapes and sizes. A spring 39 fixed at its ends to the 85 under sides of arms 30 and 31 tends to draw the same together to engage and hold a lens placed on the anvil 28, and a convenient manually operable means is provided for separating the arms when inserting or removing a lens comprising preferably a 90 lever 40 pivoted on a stud 41 carried by the fixed channel member 34 between the shoes 36 and 37. The opposite ends of lever 40 extend opposite the shoes and are slotted to loosely engage pins 42 carried by the shoes. Lever 40 carries a handle 43 extending beyond the end of channel member 34 at the 95 right hand side of the machine for convenient operation of the lens gripping means, and it is apparent that the latter is adapted 100 to support a lens with the center of one side resting on anvil 28. A cover plate or housing 43^a fixed to the forwardly extending flanges of the channel member 34 encloses 105 these operating parts.

The means for sliding sleeve 26 vertically on standard 25 to move the lens holding device toward and from the cutting element comprises, preferably, a lever 44 slotted at its left hand end, Figure 2, for loose engagement with a stud 45 fixed in a boss 46, Figure 3, on bearing 17 of the frame. Lever 44 is formed with a forked portion indicated generally at 48, Figure 3, the arms of which 115 embrace sleeve 26 and are formed with bearings 49 receiving trunnions 50 carried by the sleeve and forming a pivotal connection between the latter and the lever. One of the arms of the lever is extended toward the right hand side of the machine to provide a handle 51 by the vertical movement of which sleeve 26 and the lens holding device may be raised to bring the lens and disk 20 into cutting engagement with each other.

Means are provided for accurately con- 120

- trolling the degree of approach of the lens anvil and cutting element comprising preferably a micrometer device for adjusting the height to which the anvil is raised by the 5 raising of the sleeve 26. Such adjusting device may be incorporated in any suitable manner, being in the present instance carried at the upper end of standard 25 and serving as an adjustable stop limiting the 10 upward movement of sleeve 26. As shown in Figure 5 the frame of the standard has a threaded bore or opening 52 in which is threadedly engaged a stud 53. The outer end of bore 52 is enlarged and slidably receives the reduced lower end 55 of one of the 15 micrometer parts 54 which is slidably carried on stud 53. The end 55 of part 54, Figure 7, is keyed or splined to standard 25 so that it may slide vertically in the opening in the latter but is held against rotation, and this portion 55 is threaded as at 56 for engagement with a collar 57 disposed as shown between the upper end of standard 25 and a shoulder formed by the lower end of 20 an enlargement 58 on the part 54. Portion 58 is also threaded for engagement with a nut or collar 59 which is thus rotatably adjustable on the part 54 and forms a stop for the upper end of sleeve 26. Part 59 is beveled at its upper end as at 59^a to provide a 25 surface on which are marked the graduations of a scale 60 as shown in Figure 3. The cylindrical upper end of part 54 adjacent scale 59^a is marked with vertically spaced 30 graduations of a scale 61 and with a vertical zero line 62. It is apparent from this construction that after loosening stud 53, collar 57 may be turned or adjusted on part 54 in engagement with the upper end of the 35 standard to vertically adjust part 54 and the zero of scale 61 to compensate for variations, for example, in the radius of the cutting element. After adjustment bolt 53 may be tightened to clamp the parts in place. 40 Parts 58 and 59 with their cooperating scales thus constitute a micrometer device by means of which stop 59 may be accurately set for controlling or measuring the degree of approach of the lens anvil and cutting element. 45 In operation after adjusting micrometer parts 58, if necessary, so that the zero of the micrometer device corresponds with contact between the lens anvil and cutting element, micrometer part 59 is turned as well understood in the art to indicate the desired lens thickness. By means of handle 43 the lens gripping fingers 32 are separated and a lens placed with its lower surface on the top of anvil 28 after which release of handle 43 50 allows the fingers to grip the edges of the lens and hold the same centrally on the anvil. With the cutting element in rotation handle 51 is then raised to carry the lens into cutting engagement with the element and the cutting operation continued until sleeve 26 55 is stopped by the micrometer device which limits the approach of the anvil toward the cutting element when the latter has marked the lens at the proper distance from its opposite side. 60 As apparent from the disclosure the machine is simple, compact and practical in construction. The parts are so designed and arranged as to afford convenience in adjustment and operation and the lens blanks 65 may be quickly inserted and removed and thus rapidly and accurately provided with a guide mark facilitating the grinding of the same to the desired thickness. 70 I claim as my invention: 75
1. In a machine for forming a thickness indicating guide mark in a lens blank, the combination with a support, of a cutting element in said support, a lens holding element comprising devices adapted to engage the edge of the lens on opposite sides thereof and yieldably urged in contact therewith and opposed to said cutting element, a lens gage opposing said cutting element, a lever for moving one of said elements relatively to the other during the cutting operation, a stop for limiting the extent of the cutting operation, and means for adjusting the stop. 80
2. In a machine for forming a thickness indicating guide mark in a lens blank, the combination with a support, of a cutting element in said support, a standard a lens holding element opposed to said cutting element and slidably mounted on said standard, a lens gage on said holding element, a lever for moving said lens holding element upon said standard during the cutting operation, a stop normally spaced from said holding element for limiting the extent of the cutting operation, and micrometer devices for adjusting the stop. 85
3. In a machine for forming a thickness indicating guide mark in a lens blank, the combination with a support, of a rotary cutting element in said support adapted to contact with one face of the lens, a lens holding element opposed to said cutting element, including devices yieldably engaging the peripheral edge of the lens and a member contacting with the face of the lens opposite to that engaged by the cutting element, means for moving the holding element toward and from the cutting element to bring a lens blank on the holding element into engagement with the cutting element, stop devices for limiting the extent of movement of the holding element to limit the cutting of said blank to a predetermined thickness, and micrometer means for adjusting said stop devices. 90
4. In a machine for forming a thickness indicating guide mark in a lens blank, the combination with a support, of a rotary cutting element in said support, a lens holding element opposed to said cutting element, said 95

- 105
- 110
- 115
- 120
- 125
- 130

holding element including a pair of movable grippers adapted for a sliding movement one toward another to engage a lens between them and a lens gage adapted to engage the side of the lens opposite the cutting element, means for moving said holding element to move the lens into the path of the cutting element, and a stop for limiting the depth to which the lens blank is cut, comprising an adjustable member normally spaced from and in the path of said holding element.

5. A lens grinding machine comprising a cutting element, a plurality of relatively movable chuck parts disposed for engagement with the periphery of a lens, resilient means holding said parts in engagement with the lens, manually operable means for separating said chuck parts to receive or release 15 a lens, an anvil arranged interiorly of said chuck parts for positioning contact with the side of the lens opposite said element, said chuck parts being movable relatively to said element to bring the latter and the lens into 20 cutting engagement, and adjustable measuring means limiting the relative movement of said chuck parts and element for cutting a portion of the lens to a predetermined thickness.

30. 6. A lens marking machine comprising a rotary cutting wheel, a lens holder including an anvil for the lens disposed opposite said wheel and spaced devices yieldably engaging the peripheral edge of the lens and movable 35 with the anvil as a unit, means for moving said holder toward and from said wheel to bring the lens into cutting engagement with the wheel, and micrometer means limiting said movement of the holder for cutting a 40 mark in one side of the lens at a predetermined distance from its opposite side.

7. In a machine of the class described, the combination of a frame, a standard thereon, a support slidably on said standard, a cutting element, a lens holding element cooperating with said cutting element, one of said cooperating elements being mounted on the frame and the other on said support for movement of one toward and from the other 45 to bring the lens into engagement with the cutting element, a stop on the standard for controlling the cutting of the lens to a predetermined thickness, and micrometer devices for adjusting said stop.

55. 8. The combination of a frame, a standard thereon, a support slidably carried on said standard, a cutting element on said frame, gage means on said support provided with devices for holding a lens with one side in 60 contact with said gage means, operating means for moving said support to bring the side of the lens opposite said gage means into engagement with said cutting element, and a stop on said standard provided with 65 a micrometer adjustment for controlling the

movement of said support to cut the lens to a predetermined thickness.

9. The combination of a frame, a standard thereon, a support slidably carried on said standard, a rotary cutting wheel on said frame, an anvil on said support provided with means for holding a lens with one side in engagement therewith, means for moving said support to bring the other side of the lens into cutting engagement with said wheel, and a stop threadedly carried by said post and provided with a micrometer adjustment for controlling the degree of approach of said wheel and anvil for cutting the lens to a predetermined thickness.

70 10. The combination of a frame, a standard thereon, a support slidably carried on said standard, a rotary cutting wheel on said frame, an anvil on said support provided with relatively movable parts for gripping the lens to hold the latter with one side on said anvil, manually operable means for effecting relative movement of said parts to grip and release a lens, manually operable means for moving said support to bring the side of the lens opposite said anvil into cutting engagement with said wheel, and stop means provided with a micrometer adjustment for controlling the degree of approach of said wheel and anvil for cutting the lens to a predetermined thickness.

80 11. The combination of a frame, a support movably carried by said frame, a cutting element, a gage element cooperating with said cutting element and provided with means for holding a lens, one of said cooperating elements being mounted on said frame and the other on said support for movement of one toward and from the other to bring the side of the lens opposite said gage element into engagement with said cutting element, a micrometer part adjustably carried by said frame for adjustment to correspond with the relative positions of said cutting and gage elements, and a cooperating micrometer part adjustably carried by said first micrometer part to form a stop for said support for controlling the cutting of the lens to a predetermined thickness.

90 12. The combination of a frame, a support 100 movable carried thereby, a cutting element, a lens holding gage element, one of said elements being mounted on said frame and the other on said support for relative movement to bring the side of a lens opposite said gage element into engagement with the cutting element, a supporting and clamping stud threadedly connected with said frame, a threaded micrometer part movable on said stud, a nut threadedly engaging said micrometer part for adjustably positioning the latter relative to said frame, a second micrometer part threadedly connected with the first in cooperation therewith and forming 110 a stop for said support for controlling the 120 movement of the lens to a predetermined thickness.

130

cutting of the lens to a predetermined thickness.

13. The combination of a frame, a rotary cutting element thereon, lens holding means comprising an anvil for supporting and positioning engagement with one side of a lens, a member on said frame channelled to form a plurality of guideways, members 5
slidable in said guideways having fingers for 10
supporting engagement with the periphery of the lens, and means for holding said fingers in engagement with the lens, said lens holding means being movable to bring the side of the lens opposite said anvil into 15
engagement with the cutting element, and adjustable means limiting the degree of approach of said cutting element and anvil for controlling the cutting of the lens to a predetermined thickness.
14. The combination of a frame, a rotary cutting element thereon, lens holding means comprising an anvil for supporting and positioning engagement with one side of a lens, a member on said frame channelled to form 20
a plurality of spaced guideways, members 25
slidable in said guideways having fingers for supporting engagement with the periphery of a lens, a lever pivoted on the frame between said members and having its 30
ends connected with the latter, means tending to hold said fingers in engagement with the lens, handle means on said lever for moving the same and said fingers to receive and release the lens, said lens holding means 35
being movable to bring the side of a lens opposite said anvil into engagement with the cutting element, and adjustable means limiting the degree of approach of said cutting element and anvil for cutting of the lens to 40
a predetermined thickness.

15. In a machine for forming a thickness

indicating guide mark in a lens blank, the combination of a thin cutting disk, a slidably mounted lens carrying device including a holder and an anvil thereon arranged to support a lens in a plane at substantially right angles to the plane of the disk and a pair of slidably mounted arms upon the holder having upstanding fingers engaging the edge of the lens, a lever for moving the holder to bring the lens into cutting engagement with the disk, and stop devices for limiting the movement of the lens holding device. 45

16. In a machine for forming a thickness 50
indicating guide mark in a lens blank, the combination of a thin cutting disk, a slidably mounted lens carried device including a holder and an anvil thereon arranged to support a lens in a plane at substantially right angles to the plane of the disk, said holder having arms slidably mounted therein and provided with spring pressed means having gripping engagement with the lens, and a lever for moving the holder to bring 55
the lens into engagement with the disk. 60

17. A lens marking machine comprising a frame, a thin rotary cutting disk thereon, a standard on the frame, a support slidable on the standard, an anvil on the support for 70
engagement with one side of a lens, relatively movable members on said support for releasable engagement with the lens to hold the same on said anvil, a lever pivoted on the frame and connected with said support for moving the same to bring a lens on said anvil into tangential engagement with said disk, and micrometer means forming an adjustable stop for said support for cutting the lens to a predetermined thickness. 75

CARL L. BAUSCH.
